UNITED STATES PATENT OFFICE.

GEORGE F. McCULLY, OF NORTH VANCOUVER, AND AUGUSTUS ALEXANDER DAVIDSON,
OF VANCOUVER, BRITISH COLUMBIA, CANADA.

FAUCET.

1,321,835.

Specification of Letters Patent. Patented Nov. 18, 1919.

Application filed March 6, 1919. Serial No. 280,954.

To all whom it may concern:

Be it known that we, GEORGE F. McCULLY and AUGUSTUS ALEXANDER DAVIDSON, both subjects of the King of Great Britain, and 5 residents, respectively, in the cities of North Vancouver and Vancouver, in the Province of British Columbia, Canada, have invented certain new and useful Improvements in Faucets, of which the following is a specification.

Our invention relates to improvements in faucets, and the object of our invention is to provide a simply constructed faucet, adapted to be held closed by the pressure of the 15 water, which faucet is positive in action, operates without noise, and in which the liability of leakage is reduced to the minimum, the improvements relating particularly to the faucet described and claimed in Canadian Patent No. 169,712, granted to George F. McCullly on May 23, 1916.

We attain this object by the construction illustrated in the accompanying drawings in which—

25 Figure 1 is an outside view of the faucet. Fig. 2 is an enlarged vertical longitudinal section, taken on the center line.

Fig. 3 is a sectional elevation of the upper part of the faucet, showing the operating 30 spindle.

Fig. 4 is a detail view of the operating spindle.

Fig. 5 is a plan view of the removable valve seat.

35 Similar figures of reference indicate similar parts throughout the several views.

1 indicates the base portion of the faucet, which is provided with a threaded nipple 2, the bore of which is restricted as at 3, by 40 means of which nipple the faucet is adapted to be connected to a water conduit. The base portion is exteriorly threaded as at 4 to receive thereon the upper part 5 of the faucet, which is correspondingly threaded 45 interiorly at its lower end, as at 50, this upper part being provided with a transverse wall 6 having an opening 7, as shown in Fig. 2, which wall separates the chamber 8 of the upper part 5 from the chamber 9 of the 50 lower or base part 1, this latter chamber being in communication with the bore 10 of the nipple 2 through the restricted opening 3, as hereinafter more fully described, while the chamber 8 is in communication with the delivery spout 11, secured into the side of the

upper part in any approved fashion. The bore of the chamber 9 is undercut, as indicated at 12 in Fig. 2, so that annular upper and lower bearing strips 13 and 14 are formed adjacent the upper and lower ends 60 respectively of the chamber 9, from which it will be seen that when the liner 15 is fitted into place an annular chamber 16 is formed extending around the liner. The lower end of the liner rests on the bottom of chamber 65 9 and at a suitable height in the liner wall an aperture 17 is provided, as many of these apertures, however, being provided as are deemed necessary, while adjacent the bottom of the liner in the side thereof is formed 70 an aperture 17^a, as shown in Fig. 2.

Slidably mounted for vertical movement in the liner 15 is a hollow plunger 18, open at its upper end, its lower end being closed and provided with a restricted aperture 19, 75 as shown in Fig. 2, which plunger is provided with a groove 20 running annularly therearound on the outside thereof adjacent its upper end, an aperture or port 21 being provided through the plunger wall and positioned in the groove 20, all as shown in Fig. 2. The number of these ports 21 may correspond to the number of apertures or ports 17 in the liner. This plunger is mounted on the lower end of the valve member 22, an extension 23 on the valve member fitting an opening 24 in the closed end of the plunger, which extension projects beyond the plunger end and is fitted with a nut 23^a 80 by means of which the valve member and plunger are held together. The nut 23^a rests on the bottom of the liner 15 when the valve member is depressed so that a space 24^a is formed between the bottom of the liner and the bottom of the plunger, which space 85 communicates with the annular chamber 16 through the aperture 17^a hereinbefore mentioned. The valve member 22 is formed cylindrical, of less diameter than the bore of the plunger 18, and its upper end is 90 mitered or rounded to form a valve head 25.

Up to this point the construction described is substantially the same as that described in the Canadian patent hereinbefore mentioned, according to which construction the 105 opening 7 of the transverse wall 6 was mitered to form a valve seat co-acting with the mitered end of the valve member 22, these numerals having reference to the present specification. According to the improved 110

construction forming the subject matter of the present application the valve seat is made detachable and consists of a disk 26 adapted to fit the bore of the chamber 9 and 5 to rest on the upper bearing strip 13 and on the end of the liner 15 to keep the same in place, the upper face of the disk being flush with the upper end of the base portion so that the upper part 5 may be screwed 10 down on to the lower part to carry the wall 6 against the disk 26 and hold it in position. The disk is provided with a boss 27 extending upwardly through the opening 7 of the wall 6, through which boss extends a bore 15 28 widened at its lower end and shaped to form a valve seat 29 adapted to co-act with the upper end of the valve member 22, that is, the valve head 25, while extending upwardly through the bore 28 to project a suitable 20 distance beyond the upper end of the boss 27 is the valve member operating stem 30, which stem is secured to the upper end of the valve member in any suitable manner. This stem is reduced for a portion of its 25 length, as indicated at 31 in Fig. 2, in order to permit water to flow therearound and out through an aperture 32 in the boss 27 when the valve member 22 and plunger 18 are depressed.

30 A further improvement in the original construction described in Canadian Patent No. 169,712 resides in the arrangement for depressing the valve member 22. In that construction the operating stem extended 35 straight up through the upper part of the faucet and then slidably through a packing nut on the faucet upper end, being threaded to receive a push button. It is found preferable, however, to form a trans- 40 verse cylindrical member 33 on the upper part 5, this member being disposed at the upper end and on the rear side of the faucet. At midlength on the inside the front wall of the cylinder is cut, as indicated at 34 in 45 Figs. 2 and 3, to provide an operating space for the finger 35, which finger is mounted on a squared portion 36 of a spindle 37 passed through the bore 38 of the cylinder, the inner end of the spindle being reduced to form 50 a pintle 39 adapted to seat in a reduced bore 40 formed in the opposite inner end of the cylinder. Adjacent the squared portion 36 the spindle is provided with a collar 41 against which suitable packing 42 may be 55 forced by means of a packing nut 43 screwed into the bore 38 which is interiorly threaded correspondingly to the nut. The spindle extends through the nut and its outer end is squared, as at 44, so that the operating han- 60 dle 45 may be mounted thereon, this handle being held in place by means of a small screw 46, as shown in Figs. 3 and 4. By this construction the handle and spindle can be removed without disassembling the faucet, which is not possible with the original

construction, and further, a lever action is provided for operating the stem 30, thus enabling the spindle to be packed tighter than with the vertical compressible stem, which could not be packed tightly since the water 70 pressure might not be sufficient to overcome the stem and packing friction if packed too tight. With the present arrangement, however, the packing may be compressed to any degree of tightness irrespective of any other 75 considerations relating to the operation of the valve member and plunger.

The operation of the faucet will be readily apparent, on reference being had to Fig. 2, in which the faucet is shown open, the valve 80 member 22 and plunger 18 being depressed by means of the finger 35, which is in its lowest position, to which position it is carried by the swinging downwardly of the handle 45. During this downward movement of the 85 plunger the upward pressure of the water on its closed end is relieved by the provision of the aperture 19, thus providing for free downward movement of the plunger. The downward travel of the plunger is so arranged that, when at the end of its stroke, the aperture 21 registers with the aperture 17 of the liner 15, as shown in Fig. 2, which aperture 17 is in communication with the 90 annular chamber 16, this chamber being normally supplied with water from the conduit through aperture 3. It will thus be apparent that, when the plunger is depressed to the end of its stroke, water will flow through the aperture 3 of the nipple 10 into chamber 100 16 to pass through the liner aperture 17, the plunger aperture 21, the opening 29, the bore 28, and out through aperture 32 into chamber 8 to be discharged through the delivery 105 spout 11.

Upon release of the pressure on the stem 30 the pressure of the water flowing through aperture 17^a into the space 24^a acting on the closed end of the plunger 18 will raise the plunger, carrying the valve 25 upwardly to 110 re-seat the same on valve seat 29, thus shutting off the flow of water through spout 11 and at the same time bringing the port 21 above the port 17, from which it will be seen that water cannot now flow from the faucet. 115

What we claim as our invention is—

1. In a faucet, the combination with a casing adapted for connection to a water supply and a compressible valve adapted for manual unseating to open the faucet and 120 water-operated to reseat it and close the faucet, of a cylinder formed transversely on the upper end of the casing, the wall of said cylinder being cut at midlength to provide an opening, said cylinder having a threaded bore on one side of said opening and a plain bore on its opposite side, a spindle rotatably mounted in said cylinder having its inner end fitting the plain bore thereof and an inner squared portion in alignment with the 125 130

wall opening, the outer end of said spindle being extended through and beyond the end of the threaded bore and provided adjacent the inner squared portion with a collar and 5 being squared at its extremity to receive an operating handle, a nut mounted on the outer end of said spindle adapted to fit the threaded bore of the cylinder, and a finger mounted on the inner squared portion oper- 10 able in the said wall opening the depression of which by the operation of the spindle de- presses the valve.

2. In a faucet, the combination with a casing having delivery and pressure cham- 15 bers, a plunger vertically movable in said pressure chamber adapted to be raised by the water to close the water supply to said chamber and manually depressible to open it thereto, and a valve carried by said 20 plunger, of a valve seat member removably mounted between said chambers consisting of a disk mounted in the upper end of the pressure chamber and provided with a central boss extending upwardly into the de- 25 livery chamber having a bore the lower end of which is formed as a valve seat with which said valve co-acts in its highest position to close communication between the chambers and an aperture extending from 30 the bore through the side of the boss, a valve stem secured to said valve extending slidably through said bore and reduced in diameter

opposite said aperture, and means for de- pressing said stem.

3. In a faucet, the combination with a cas- 35 ing having delivery and pressure chambers, a plunger vertically movable in said pres- sure chamber adapted to be raised by the water to close the water supply to said chamber and manually depressible to open 40 it thereto, and a valve carried by said plunger, of a disk removably mounted in the upper end of the pressure chamber and pro- vided with a central boss extending up- 45 wardly into the delivery chamber having a bore the lower end of which is formed as a valve seat with which said valve co-acts in its highest position to close communication between the chambers and an aperture ex- 50 tends from the bore through the side of the boss, a valve stem secured to said valve extending slidably through said bore and reduced in diameter opposite said aperture, a rotatable spindle mounted transversely in the upper end of the delivery chamber, and 55 a finger mounted on said spindle adapted to coact with the said valve stem whereby the same is depressed by the depression of the finger through the operation of the spindle.

Dated at Vancouver, B. C., this 22d day of 60 February, 1919.

GEORGE F. McCULLY.
AUGUSTUS ALEXANDER DAVIDSON.
